DRAWBENCH ARM MECHANISM

Wallace E. Kerr, Youngstown, Ohio

Application September 12, 1945, Serial No. 615,831

7 Claims. (Cl. 205—22)

1

This invention relates to metal drawing equipment and more particularly to improved stock discharging arm mechanisms for drawbenches.

In metal drawing apparatus employing a die and a bench extending outwardly therefrom as well as a grip carriage supported on the bench it has been heretofore proposed to provide horizontally swinging arms spaced outwardly along the bench and to swing these arms in succession under the stock piece being drawn as the grip carriage moves outwardly. In certain of these systems means is provided to rock the extended arms upwardly after the stock piece is free of the die and carriage thereby ejecting the drawn stock piece from the bench. In other systems the arms are retracted horizontally and upwardly knobs on the free ends of the arms engage and move the stock piece off of the bench or, in the case of round stock, the arms may be sloped and be retracted by swinging horizontally only after the stock piece has rolled off.

Regardless of the specific nature of the discharge arm mechanism as heretofore employed the arms were so positioned that in swinging to extended positions they would pass under a stock piece of the maximum dimension which the machine was capable of handling. Now if smaller sections were being drawn the stock piece would sag down behind the grip carriage with a tendency of the gripped end to wedge in the grips. Upon the stock piece moving clear of the die and the consequent opening of the grips the stock piece would not always be freed from the grips, and would then have to be removed by hand. The present invention overcomes this difficulty by snugly supporting the stock piece immediately prior to and during completion of the draw so as to avoid the above described canting and stocking of the stock piece in the grippers.

A further object of the invention is to provide an arrangement for further facilitating the disengagement of the grip carriage from the stock piece at the completion of a draw and this is accomplished by restraining forward movement of the stock piece after completion of the draw.

Another object of the invention is to provide a drawbench discharge arm mechanism of the upward tilting type with resilient means to resist abrupt downward movement of the arm. Thus the arm mechanism is protected against severe impacts which sometime occur when the stock pieces jump free of the die.

Yet another object of the invention is to provide in a drawbench discharge arm mechanism

2

of the upward tilting type means to tilt the arms slightly to snugly support the stock piece at the completion of a draw and adjustable means on the arms forming horizontal supporting surfaces for different sizes of stock pieces. By supporting the stock pieces on horizontal surfaces at the time of the completion of the draws the tendency of the stock pieces to cant or twist sideways is minimized and their disengagement from the grip carriage is thus facilitated.

Other objects of the invention include the provision of improved operating or driving arrangements for drawbench discharge arms of the horizontal swinging and upward tilting type and of an improved release mechanism for the latched arms. Further objects and advantages of the invention will become apparent upon consideration of the following detailed specification and accompanying drawing wherein there is disclosed a preferred embodiment of the invention.

In the drawing:

Figures 1 and 2 are plan and side views, respectively, of a drawbench discharge arm mechanism constructed in accordance with the principles of the invention:

Figures 3 and 4 are transverse sections taken along the lines 3—3 and 4—4, respectively, of Figure 2;

Figures 5 and 6 are plan views of the arm latching arrangements utilized in the assembly of Figures 1 and 2;

Figures 7 and 8 are plan views illustrating the two limiting positions of the arm operating crank and cylinder assembly utilized in the machine of Figures 1 and 2;

Figure 9 is a fragmentary section illustrating a part of the rock shaft limit switch operator;

Figure 10 is a schematic diagram of a control system which may be advantageously employed in connection with the machine of Figures 1 and 2; and

Figure 10a is an elevation of the rock-shaft limit switch.

Referring to the drawing, reference numeral 10 designates a die block or stand in which is positioned the die through which the stock is to be drawn. Extending outwardly beyond the die block 10 is a bench 11 along which travels a carriage 12 mounting a pair of stock grippers 13. In accordance with usual practice, means such as a chin, not shown, is employed to move the carriage outwardly in drawing direction and other means as a cable, not shown, may be employed to return the carriage 12 to the die block 10.

Journaled in spaced brackets 14, which are secured to the right side of the bench 11, is a heavy longitudinally extending shaft 15. Shaft 15 is arranged to be rocked about its principal axis and mounts the discharge arm assemblies now to be described.

Each of the discharge arm assemblies comprises a housing 16, which is rigidly clamped to the shaft 15 by means of the clamp bolts 17, for example. Journaled in the housing 16 is a pin 18 to the upper end of which is keyed an arm 19 and to the lower end of which is keyed a crank 20. Pivoted supported from an integral extension 21 of the housing 16 is a simple hydraulic cylinder 22 containing a piston the connecting rod of which is coupled with the crank 20. Extending outwardly from a boss also formed integral with housing 16 is a rod 23 to the outer free end of which is attached on end of a coil spring 24. The opposite end of spring 24 is connected with the outer free end of a crank arm 25 which is rigidly connected with the lower end of the pin of the crank 20. Formed as an integral part of the arm 19 or independently keyed to the pin 18 is a latch ring, two types of which are utilized in the illustrated embodiment of the complete system. The first of these rings, indicated by the reference numeral 26, is shown in detail in Figure 5 and is utilized in the discharge arm assembly which is closest to the die block 10. As shown, latch 26 has a segmental detent 27 substantially aligned with the longitudinal axis of arm 19 and a second ratchet detent 28 positioned on the outward side of the arm 19 when the arm is in extended position. Each of the other arm assemblies has a latch ring 29 which is identical with the latch 26 except in the omission of the second detent 28.

Latches 26 and 29 are arranged to be operatively engaged by the dogs 30, one of which is pivotally mounted on each of the housings 16 in position to be tripped by a gate type of operator 31 mounted on the carriage 12. Spring means, not shown, is employed to bias the dogs 30 into engagement with the latches 26 and 29 as shown in Figures 1, 5 and 6. Figures 5 and 6 show the arms in extended position, of course, so that if the arms are now rotated proximately 90° in a counter-clockwise direction to retracted positions the dogs 30 will engage the shoulders of detents 26 to retain the arms in such positions. Such retraction is accomplished by the cylinders 22 and Figure 7 shows relative position of one of the cranks 20 when the arm associated therewith is in extended position. Figure 8 shows the relative position of the parts when the arm is retracted.

The means employed to rock the shaft 15 comprises a cylinder 32 which is pivotally mounted at 33 on a bracket 34 secured to and extending downwardly and outwardly from the bench 11. Bracket 34 extends on the opposite side of the bench 11 from the shaft 15. Cylinder 32 is of the double acting type and has its piston rod connected with the crosshead 34'. Extending through spaced apertures in crosshead 34 and through apertures formed in the outer end of pins 35 is a pair of pull rods 36. The right ends of pull rods 36 are connected with a pivot pin 37 which passes through the lower end of a lever 38 which is rigidly keyed to the shaft 15. The ends of the rods 36 which pass through the crosshead 34' have retaining nuts 39 and coil springs 40 interposed between the nuts 39 and the mem-

ber 34. There is thus provided a yieldable driving connection, the purpose of which will be explained in detail below.

I provide a source of hydraulic fluid pressure comprising a conduit 41 which leads to four-way valve 42 which controls the operation of cylinder 32 and also to a three-way valve 43 which controls the flow of fluid into and out of cylinders 22. As shown in Figures 1 and 10, valve 42 is provided with ports which are connected with opposite ends of cylinder 32 while valve 43 has a port which is connected with a supply line 44 leading to all the cylinders 22. Valves 42 and 43 have exhaust ports connected with a fluid return conduit. Valve 42 is of the self-centering type and when centered all the ports are blocked. The core is moved in one direction by a solenoid 42U and when this solenoid is energized fluid pressure is admitted to the inner end of cylinder 32 to rotate the shaft 15 in the direction tending to rock the arms 19 upwardly (assuming these arms to be in extended positions). A second solenoid 42D operates the core of valve 42 and is operative when energized to actuate valve 42 in such manner that fluid is admitted to the outer end of cylinder 32 to rock shaft 15 in the opposite direction. It should be remembered that at any time when both solenoids 42U and 42D are de-energized the piston in cylinder 32 will be locked in the particular position it has assumed at that time. Valve 43 is operated by a solenoid 43R and upon energization connects conduits 41 and 44 while blocking the exhaust port. When the solenoid 43R is de-energized conduit 44 is connected with the return line 45 and the supply ports of the valve 43 are blocked.

I provide a novel system for controlling the mechanism described above in a highly advantageous manner and such control system may comprise relays R1, R2, R3, and R4 as well as various limit switches operated in response to the rotated position of the shaft 15 and in response to positions of the grip carriage 12, and various manual control switches to be hereinafter described in detail. As to the carriage operated switches, normally closed switch 46 is positioned adjacent the die head 10 and is arranged to be opened when the carriage is adjacent to the die head. Next outwardly along the bench is a normally closed limit switch 47 the primary function of which is to slow down the return movement of the grip carriage (not a feature of the present invention). Mounted at an adjustable position further outwardly along the bench is a third normally opened limit switch 48 the function of which is to effect slight initial rotation of the shaft 15 in the direction necessary to bring the arms 19 up against the stock piece being drawn for the purpose initially explained. The fourth limit switch 49, which may comprise a pair of switches in series, is associated with one or two of the discharge arms and is arranged to be closed when this arm (or arms) is in retracted, latched position.

The controlling limit switches which are operative in response to the rotated position of shaft 15 are the normally open switches S2 and S3 and the normally closed switches S4 and S1. These four switches are adjustably (circumferentially) mounted in a drum 50 secured to the side of bench 11 opposite shaft 15. These four switches are arranged to be operated by a diametrically opposed pair of spokes 51 and 52 projecting outwardly from a hub 53 keyed to a shaft

54. Shaft 54 is arranged to be rotated in proportion to the rotation of shaft 15 by means of the gears 55 which effect multiplication of the motion of the shaft 15. As viewed in Figure 10, shaft 54 rotates clock-wise as shaft 15 rocks to move arms 19 upwardly.

A manual switch 56 having normally closed contacts 57 and normally open contacts 58 is provided to effect "rock-up" of the arms 19 under manual control while a manual switch 59 having normally closed contacts 60 and normally open contacts 61 is provided to effect retraction of the arms 19 under manual control. Normally the grip carriage return motor, not shown, is energized automatically (upon actuation of a switch 49) but under certain circumstances it may be desirable to effect energization under manual control and for this purpose I provide a normally open manually controlled switch 62. A manual switch 63 is in parallel with limit switch 48.

At the start of a draw the arms 19 are latched parallel with the bench and as evident from Figures 1, 2 and 8 the springs 24 are tensioned tending to swing the arms across the bench. As the carriage 12 passes each arm assembly the operator 31 trips the dogs 30 allowing the arms to swing to transverse positions in back of the carriage and the arms are maintained in such positions by reason of the crank arrangement (25) as will be understood. The detent 28 in the latch of the first arm prevents this first arm from swinging beyond transverse position while the succeeding arms are free to swing in either direction from transverse or extended positions. As the draw approaches completion limit switch 48 is closed by the carriage to energize relay R1 through a circuit-line conductor L1, contacts 57, conductors 65 and 66, contacts 60, conductors 67 and 68, switch 48, conductors 69 and 75, contactor 1R4 of relay R4, conductor 70, contactor 1R2 of relay R2, conductor 71, relay coil R1, and conductors 72 and 73 to line conductor L2. A holding circuit for relay R1 is provided through conductor 67, conductor 74, contactor 1R1 of relay R1, conductors 76 and 75, contactor 1R4, conductor 70, contactor 1R2 and conductor 71. At this time solenoid 42U is energized through the circuit conductor L1, contacts 57, conductors 65 and 66, contacts 60, conductors 67, 74 and 74', contactor 1R1, conductor 76, limit switch S4, conductors 77 and 78, solenoid 42U, and conductor 79 to line conductor L2. Fluid is now admitted to inner end of cylinder 32 and when the shaft 15 is rocked sufficiently to bring the upper surfaces of the arms 19 almost into engagement with the stock piece being drawn limit switch S4 is actuated (opened) to de-energize solenoid 42U whereupon the piston in cylinder 32 is locked in its current position. Now as the stock piece leaves the die the same will be supported in direct alignment with the grippers on carriage 12 so that upon opening of these grippers the same may be moved freely away from the end of the stock piece. Such disengagement is abetted by the locking of the first arm (detent 28) against swinging movement in the direction following the movement of the carriage.

Upon the stock piece being free of the die and carriage the operator may eject the piece from the machine by depressing switch 56 which establishes the circuit-conductor L1, contacts 58, conductors 80 and 78, solenoid 42U, and conductor 79 to line conductor L2. The arms 19 now tilt upwardly and the position response operator 51

closes switch S3 to energize relay R2 through the circuit-conductors L1 and 81, switch S3, conductor 82, the coil of relay R2, and conductors 83 and 73 to line conductor L2. A holding circuit for relay R2 is established through line conductor L1, conductor 84, switch 47, conductor 85, contactor 2R2 of relay R2, conductors 86 and 82, coil of relay R2, and conductors 83 and 73 to line conductor L2. Relay R2 has a third contactor 3R2 so that upon the ejecting of the stock piece and the release of switch 56 solenoid 42U will be de-energized (opening of contact 58) and solenoid 42D energized, the latter through the circuit-conductor L1, contacts 57, conductors 65, 87, 88, a contactor 2R1 of relay R1, conductor 89, contactor 3R2, conductor 90, limit switch S1, conductor 91, solenoid 42D, and conductor 79 to conductor L2. While the arms 19 move to their down positions switch S2 is closed to energize relay R3 through the circuit conductor L1, contacts 57, conductors 65, 87, 88, contactor 2R1, conductor 89, contactor 3R2, conductor 90, switch S2, conductor 92, coil of relay R3, and conductor 93 to conductor 12. A holding circuit for relay R3 is established through conductors L1 and 84, switch 47, conductor 85, contactor 2R2, conductors 86 and 94, contactor 1R3, conductor 95, coil of relay R3, and conductor 93 to conductor L2. When the arms reach non-tilted positions switch S1 opens to de-energize solenoid 42D.

Relay R3 is provided with a second contactor 2R3 which energizes solenoid 43R through circuit-conductor L1, contactor 57, conductors 65, 87, and 95, contactor 2R3, conductors 96 and 103, solenoid 43R, and conductors 97' and 79 to conductor L2. This admits fluid pressure to cylinders 22 and the arms are retracted and latched in positions parallel with the bench. Upon this being accomplished the carriage may be returned and for automatic operation I provide relay R3 with the third contactor 3R3 which energizes relay R4 through the circuit conductor L1, switch 49, conductor 97, contactor 3R3, conductors 98 and 99, coil of relay R4, and conductors 100 and 73 to conductor L2. Relay R4 has a contactor 2R4 which, upon closing, energizes the carriage return motor, not shown. A holding circuit is provided for relay R4 consisting of conductor L1, conductor 101, switch 46, conductor 102, contactor 3R4, conductor 99, the coil of relay R4, and conductors 100 and 73 to conductors L2.

As the carriage returns switch 47 is engaged and opened thus de-energizing relay R2 and relay R3, switch 47, being in the holding circuits for these relays. Relay R1 is de-energized at the time relay R2 is initially energized and so all the solenoids are de-energized. Carriage 12 continues toward the die block and opening of switch 60 46 de-energizes relay R4 thus restoring the system to its initial state preparatory to its next succeeding cycle of operation.

The arm 19 may be retracted at any time under manual control by depressing switch 59 which energizes the solenoid 43R through the circuit-conductor L1, contacts 57, conductors 65 and 66, contacts 61, conductor 103, solenoid 43R, and conductors 97' and 79 to conductor L2. The arms may be tilted upwardly a slight distance by depressing switch 63, the energizing circuit for solenoid 42U being traceable through conductors 74 and 74', contactor 3R1, conductor 76', switch S4, and conductors 77 and 78 to solenoid 42U. The grip carriage may be returned under manual control by depressing switch 62 which

establishes the circuit—conductors 11, 104, switch 62, and conductors 105 and 99 to coil of relay of R4.

To provide the generally horizontal surfaces for supporting the stock pieces immediately upon their disengagement from the die and grip, I detachably mount a block 107 on each of the arms 19 (Figure 3). The blocks 107 are secured to the top surfaces of arms 19 by the equidistant cap screws 108 and each of the blocks 107 is provided with the three inclined surfaces 109, 110, 111. Thus, for stock of large diameter or transverse dimension the surface 110 will engage the stock and since this surface makes but a small angle with the top surface of the arm proper the arm need tilt but a small amount to bring surface 110 to horizontal position. This large stock does not, of course, require much tilting movement of the arms to bring them into engagement with the stock. For smaller size stock the arms must tilt up further and this extra angularity is compensated for by the greater slope of surface 109 which then engages the stock. By pivoting block 107 about the center cap screw the third surface 111 may be employed for a still smaller size of stock and if desired this third surface may be slightly concaved as shown in Figure 3.

It should be observed that upon retraction of the arms from upwardly tilted and extended positions (immediately after ejection of a stock piece) by the cylinders 22 the arms will swing through downwardly inclined arcs and the weight of the arms will therefore exert a progressively increasing torque in a downward direction. This torque augments the forces exerted by cylinders 22, which aid is particularly advantageous as the efficiency of the cylinders 22 diminishes toward the ends of their strokes. Compare Figures 7 and 8. This increasing torque also counteracts the increasing opposing forces exerted by the expanding springs 24.

During normal retraction of the arms both the solenoids 42D and 43R are energized so that the tilting cylinder 32 and swinging cylinder 22 are simultaneously supplied with fluid from a common source. By referring to Figure 3 it will be noted that the arm assemblies are over-balanced in an outward direction, particularly when the arms 19 are extended and tilted upwardly and so appreciable pressure is required to tilt the arm downwardly. Less pressure is required to retract the arms (by cylinders 22) and consequently the fluid will first flow into the cylinders 22 to complete the retraction of the arms in the manner described in the paragraph immediately above before sufficient pressure is built up in cylinder 32 to rock the shaft 15 and bring the housing 16 into their initial vertically aligned positions.

While normally it is desirable to delay the release of the arms sufficiently to enable the grip carriage to move some distance past the extended position of the particular arm to avoid excessive impact of the arm against the carriage, it may be desirable to prematurely release that arm which is closest to the stock point when the stock piece leaves the die so that the released swinging arm follows directly in back of the carriage. This may be accomplished by providing the dog (30) of the last arm assembly used with a vertical extension 112 (Figures 2 and 4) which is engaged and operated only by a gate type of operator 113 which is positioned on the carriage 12 higher and more to the front than the operator 31. The extension of 112 is readily detachable from the

dog 30 so that it may be readily applied to any of the arm mechanisms. This feature is of advantage particularly in the case of short or limber stock as will be understood.

The operation of the above described apparatus should be readily apparent, if it is remembered that the operation of the discharge arm system is entirely automatic (normally) except for actual discharge of the stock by manually depressing switch 56. At the start of the draw the arms are in retracted horizontal positions parallel with the bench and as the grip carriage moves past the respective arms the arms are released and extended across the bench under the stock piece being drawn. Near the completion of the draw the carriage closes switch 48 which energizes relay R1, the contactor 1R1 of which energizes solenoid 42U through limit switch S4. The position of the latter is adjustable, of course, so that upon the arms contacting the work piece rotation of shaft 15 is halted and locked (by the fluid in cylinder 32 and valve 42). When the operator observes that the stock piece is clear of the die and grip carriage he may depress switch 56 to energize solenoid 42U irrespective of the open switch S4 and through switch S3 relay R2 is energized when the arms reach their upper positions and the stock piece is ejected. Closing of relay R2 de-energizes relay R1 and solenoid 42U while energizing solenoid 42D to tilt the arms downwardly. During all this time the carriage may be beyond switch 48 but it cannot be returned until relays R3 and R4 are energized. Relay R3 is energized initially only in response to the closing of switch S2 and this switch is not effectively closed until the arms are tilted downwardly a predetermined extent. Upon energization of relays R3 and R4 the grip carriage returns to the die block until opening of switch 46 de-energizes relay R4 to stop its further movement.

If desired, the limit switch S2 as well as the relay R3 may be eliminated from the control circuit described above and additional contactors provided on the relay R2 so that immediately upon the arms attaining their upper tilted positions and the subsequent release of switch 56 both the solenoids 43R and 42D will be simultaneously energized. In this alternate method of control the arms, of course, will first be retracted before the shaft 15 retracts to bring the arms to horizontal positions for reasons pointed out above. Also, if desired, switch 49 may be located in other relations to the discharge arm mechanism that it is closed only when the arms are in retracted, latched positions. Thus, the grip carriage cannot begin its return movement until the arms are retracted and latched.

The above specifically described embodiment of the invention should be considered as illustrative only since obviously many changes may be made therein without departing from the spirit or scope of the invention. Reference should therefore be had to the appending claims in determining the scope of the invention.

What I claim is:

1. A metal drawing apparatus having a grip carriage and a discharge arm adapted to be moved to operative position below the stock piece being drawn and mounted for upward tilting movement to support the stock piece in approximate alignment with the grip on said carriage, means for effecting said upward tilting movement of said arm and adjustable means for limiting the extent of said upward tilting movement, said

arm having an angularly disposed upper plane surface which will assume substantially a horizontal position when the arm is tilted upwardly to engage said stock piece.

2. In metal drawing apparatus having a discharge arm adapted to assume an operative position below a stock piece being drawn and being mounted for upward tilting movement, means for effecting said upward tilting movement of said arm, and adjustable means for limiting the extent of said upward tilting movement, said discharge arm having a separable member on its upper surface mounted for end-for-end interchange on said arm, said separable member having different angularly related supporting surfaces adjacent its ends.

3. In metal drawing apparatus having a die, a grip carriage movable away from said die, discharge arms mounted for movement from positions outside the path of travel of said carriage to positions below the stock piece being drawn and intermediate the die and grip carriage, and means for moving said discharge arms in an upward direction when in said operative positions; the combination with said arms of operating means to move said arms upwardly, and means operative upon said arms reaching upper positions immediately below the stock piece being drawn to interrupt actuation of said operating means whereby the horizontal position and alignment of said stock piece is maintained during the disengagement of said stock piece from said die and carriage.

4. The combination of claim 3 further including means to re-initiate actuation of said operating means for effecting further upward movement of said arms to eject the stock piece from said apparatus.

5. In metal drawing apparatus having a die, a grip carriage movable away from said die, discharge arms mounted for movement from positions outside the path of travel of said carriage to positions below the stock piece being drawn and intermediate the die and grip carriage, and means for moving said discharge arms in an upward direction when in said operative positions; the combination with said arms of operating means to move said arms upwardly, means to initiate actuation of said operating means upon said carriage reaching a predetermined position outwardly of said die during a drawing period, and adjustable means to interrupt actuation of said operating means upon said arms reaching an upper position immediately below said stock piece whereby the horizontal position and alignment of said stock piece is maintained during the

disengagement of said stock piece from said die and carriage.

5. The combination of claim 5 further including means to re-initiate actuation of said operating means for effecting further upward movement of said arms to eject the stock piece from said apparatus.

7. A metal drawing apparatus having a bench, a support pivotally mounted on one side of said bench for pivotal movement about an axis extending generally parallel with said bench, an upwardly extending shaft journaled in said support, a discharge arm rigidly mounted at an end on the upper end of said shaft and adapted to extend horizontally across the bench when said support is in one position and to be tilted upwardly upon said support being rotated about said axis from said one position to a second position, said arm being adapted to swing downwardly upon rotation of said shaft from said upwardly tilted position to a generally horizontal retracted tilted position parallel with said bench, said shaft having a double-throw crank thereon of which the respective throws are substantially quadrantly related, power means engaging one throw of said crank to exert thereagainst a rectilinear force in one general direction with respect to said support, said crank and power means being so oriented with respect to the length of said arm that upon said arm being in upwardly tilted position said power means exerts a maximum of torque on said shaft in a direction tending to move said arm to said horizontally retracted tilted position while upon said arm reaching said latter position said torque diminishes to zero, and means engaging the other of said throws of said crank to exert thereagainst a yielding rectilinear force in the said general direction with respect to said support whereby said last mentioned means exerts a progressively increasing torque on said shaft opposing the diminishing torque exerted by said power means and the increasing torque exerted by the gravity of the arm upon said arm moving from said upwardly tilted position to horizontal 40 retracted tilted position.
